UNITED STATES PATENT OFFICE

91,573

DESIGN FOR A LAMP BRACKET

Herbert R. Sulzer, Lower Gwynedd, Pa.

Application December 1, 1933. Serial No. 49,917

Term of patent 7 years

To all whom it may concern:

Be it known that I, HERBERT R. SULZER, a citizen of the United States, residing at Lower Gwynedd, in the county of Montgomery and State of Pennsylvania, have invented a new, original, and ornamental Design for a Lamp Bracket, of which the following is a specification, reference being had to the accompanying drawing, forming part thereof.

Fig. 2 is a front elevation thereof.

I claim:

The ornamental design for a lamp bracket as shown.

In testimony whereof, I have hereunto signed my name.

HERBERT R. SULZER.
